Primary Examiner—Carol Rademaker

(74) Attorney, Agent, or Firm—Jeffer, Mangels, Butler & Marmaro LLP

(57) **CLAIM**

The ornamental design for a bottle, as shown and described.

DESCRIPTION

FIG. 1 is a perspective view of a bottle embodying my new design, the bottle being opaque;

FIG. 2 is a top plan view of the bottle of FIG. 1;

FIG. 3 is a side elevational view of the bottle of FIG. 1;

FIG. 4 is a perspective view of a second embodiment of the bottle embodying my new design, the bottle being opaque;

FIG. 5 is a top plan view of the bottle of FIG. 4;

FIG. 6 is a side elevational view of the bottle of FIG. 4;

FIG. 7 is a perspective view of a third embodiment of the bottle embodying my new design, the bottle being transparent;

FIG. 8 is a top plan view of the bottle of FIG. 7;

FIG. 9 is a side elevational view of the bottle of FIG. 7;

FIG. 10 is a perspective view of a fourth embodiment of the bottle embodying my new design, the bottle being transparent;

FIG. 11 is a top plan view of the bottle of FIG. 10; and,

FIG. 12 is a side elevational view of the bottle of FIG. 10. The broken line showing in FIGS. 1-12 is for environmental purposes only and forms no part of the claimed design.
